UNITED STATES PATENT OFFICE.

GEORGE F. DICKSON, OF CHICAGO, ILLINOIS, ASSIGNOR TO CONFECTIONERS AND BAKERS SUPPLY CO., A CORPORATION OF ILLINOIS.

CONFECTIONER'S SIZING AND CUTTING MACHINE.

No. 809,498.

Specification of Letters Patent.

Patented Jan. 9, 1906.

Application filed December 10, 1904. Serial No. 236,293.

To all whom it may concern:

Be it known that I, GEORGE F. DICKSON, a citizen of the United States of America, and a resident of Chicago, in the county of Cook and State of Illinois, have invented certain new and useful Improvements in Confectioners' Sizing and Cutting Machines, of which the following is a specification.

This invention relates to that class of machines employed in rolling, sizing, and cutting candy and like plastic substances, and has for its object to provide a simple and efficient structural formation and combination of parts adapted to permit of a ready and rapid change from a position adapted for the operation of sizing the material to a position adapted for the operation of cutting the material, and vice versa, as will hereinafter more fully appear and be more particularly pointed out in the claims.

In the accompanying drawings, Figure 1 is a detail vertical elevation at line x x , Fig. 3, of a sizing and cutting machine embodying the present improvement with the parts in position for effecting the cutting operation. Fig. 2 is a similar view with the parts in position for effecting the sizing operation. Fig. 3 is a detail front elevation of the machine with the parts in the position described in connection with Fig. 1. Fig. 4 is a fragmentary side elevation illustrating the locking mechanism by which the series of sizing and cutting rolls of the present mechanism are secured at their different adjustments. Fig. 5 is a detail vertical section illustrating a modified arrangement of the series of sizing and cutting rolls.

Similar numerals of reference indicate like parts in the several views.

Referring to the drawings, 1 is a horizontal bed or table supported by the usual vertical side frames 2 and provided with vertical longitudinally-extending side plates, by which the material operated on is confined to a longitudinal movement along the bed.

3 is a transverse feed-roll journaled in stationary bearings in the side frames 2 and arranged in an opening formed therefor in the bed or table. Such roll is preferably formed with longitudinal corrugations in order to afford a more positive and effective feed of the material through the machine.

4 represents counterpart adjustable slides

guided vertically in vertical extensions 5 of the side frames aforesaid.

6 represents counterpart vertical screws journaled in the extensions 5 and having engagement with the slides 4 and adapted to impart vertical adjustment to the same.

7 is a transversely-extending shaft provided at one end with an operating handle or wheel 8 and having bevel-gear connections 9 with the vertical adjusting-screws 6 to impart simultaneous movement to the same.

10 represents a pair of end heads or blocks carried by a transverse shaft 11, which in turn is journaled in the adjustable slides 4, the arrangement admitting a turning movement of the end heads or blocks 10 upon the bearings of said shaft in the slides 4 aforesaid.

12 is a hand-crank carried by the shaft 11 for the convenient turning adjustment of the same by hand.

13 is a locking-disk carried by the shaft 11 and improved with a series of peripheral notches for engagement with the locking-bolt by which the said shaft is locked at any desired point in its turning adjustment.

14 is the latch-bolt above referred to moving in guides on the main frame and engaged by a spring 15, the tendency of which is to force the point of the bolt into engagement with an adjacent peripheral notch of the locking-disk aforesaid. 16 is a hand-lever engaging said latch-bolt to afford means for withdrawing the bolt from its engagement with the locking-disk when it is desired to effect a turning adjustment of the end heads 10 aforesaid.

17 and 18 are two or more rolls journaled in the turning heads or blocks 10 transversely of the machine, and such rolls are preferably of a uniform diameter with their axis of rotation concentric with the axis of the shaft 11.

In the simpler and usual form of the present invention, as illustrated in Figs. 1, 2, and 3, the construction will comprise a pair of such rolls, one roll, 17, having a plain cylindrical periphery to constitute the sizing-roll of the machine for reducing the material to the required size or thickness, and the other roll, 18, consisting of a series of circular knives secured in separated relation upon a carrying-shaft to constitute the cutting-roll of the machine for cutting the material into

- sections as such material is fed longitudinally along the machine-bed by the feed-roll 3, as illustrated in Fig. 1. The machine as so arranged is adapted to cut the material into squares by giving such material a quarter-turn upon the machine-bed and a second passage beneath the aforesaid cutting-roll. By the substitution of one or more cutting-rolls having circular cutting-knives the spaced relation of which differ the material can be cut into corresponding-sized pieces to suit the varied requirements of a particular trade. The scope of the present invention, however, embraces the arrangement of a number of said cutting-rolls with differently-spaced blades in the heads 10 with a view to the greatest degree of convenience where the machine is required to be frequently changed for the production of pieces of different sizes 20 and so that one cutting-roll may be employed to cut the material in one direction and another cutting-roll having differently-spaced cutting-blades employed to cut the material in the other direction and produce pieces of the material having an oblong form. In Fig. 5 such arrangement is shown, and comprises one sizing or flattening roll 17 and a series of three cutting-rolls 18, journaled symmetrically in the heads 10.
- 19 represents clearing-bars arranged between the series of circular blades of the cutting-roll 18 to prevent the adherence of the material between the blades.
- 20 represents transverse supporting-rods 35 attached to the heads 10 and having connection with the ends of the clearing-bars 19 by elongated slots 21 in said bars, so that the same are permitted a limited independent vertical movement with relation to said bars 40 and the circular cutting-blades, as usual in the present class of machines.
- 22 is a central gear-wheel the axis of which is the same as the axis of the journal-shaft 11 of the turning-heads 10.
- 23 represents gear-wheels on the shafts of the respective sizing and cutting rolls 17 and 18, gearing with the central gear-wheel 22 and receiving motion therefrom.
- 24 is a train of gear-wheels having driving 50 connection with the carrying shaft or sleeve of the central gear-wheel 22 and with the shaft of the feed-roll 3, so as to impart uniform and simultaneous rotation to the different rolls of the machine.
- 55 Suitable means may be provided for the ready reversal of the direction of rotation of the mechanism; but such provision forms no part of the present invention, and in consequence is not shown or described in detail.
- 60 In the operation of the present machine the heads 10 are turned in the vertically-adjustable slides 4 to bring the sizing-roll 17 in adjacent vertical relation to the feed-roll 3, after which the slides 4 are adjusted vertically by means heretofore described to bring

the sizing-roll 17 the proper distance from the feed-roll 3. The material, supported on a suitable base plate or board, if necessary, is then entered between said rolls and in its passage between the same is reduced to the required size or thickness. The heads 10 are then turned to bring the cutting-roll 18 into adjacent relation to the feed-roll 3, at the same time moving the sizing-roll 17 into an inactive position, after which the material is 70 entered between said rolls and in its passage is divided into a series of longitudinal strips. The material is then given a quarter-turn upon the machine-bed 1 and again entered between said rolls and in its passage is 75 divided into a series of small pieces or squares of the required size.

Having thus fully described my said invention, what I claim as new, and desire to secure by Letters Patent, is—

1. In a sizing and cutting machine for candy and the like, the combination of a supporting-bed, a series of sizing and cutting rolls journaled in parallel relation above said bed in supporting-heads, which in turn are 90 journaled above said bed, means for locking said heads at points in their circular adjustment, and means for feeding the material along said bed, substantially as set forth.

2. In a sizing and cutting machine for 95 candy and the like, the combination of a supporting-frame, a bed secured to said frame, heads or supports journaled in said frame and adapted for a turning adjustment, a sizing-roll and a cutting-roll journaled in parallel 100 relation in said heads, and means for feeding the material along said bed, substantially as set forth.

3. In a sizing and cutting machine for candy and the like, the combination of a supporting-frame, a bed secured to said frame, vertically-adjustable slides on said frame, heads or supports journaled on said slides and adapted for a turning adjustment thereon, a sizing-roll and a cutting-roll journaled 110 in parallel relation on said heads, and means for feeding the material along said bed, substantially as set forth.

4. In a sizing and cutting machine for candy and the like, the combination of a supporting-frame, a bed secured to said frame, heads or supports journaled in said frame and adapted for a turning adjustment, a sizing-roll and a cutting-roll journaled in parallel 115 relation in said heads, and a feed-roll journaled 120 in the main frame beneath the rolls aforesaid, substantially as set forth.

5. In a sizing and cutting machine for candy and the like, the combination of a supporting-frame, a bed secured to said frame, vertically-adjustable slides on said frame, heads or supports journaled on said slides and adapted for a turning adjustment thereon, a sizing-roll and a cutting-roll journaled in parallel 125 relation on said heads, and a feed-roll 130

journalized in the main frame beneath the rolls aforesaid, substantially as set forth.

6. In a sizing and cutting machine for candy and the like, the combination of a supporting-frame, a bed secured to said frame, heads or supports journaled in said frame and adapted for a turning adjustment, a sizing-roll and a cutting-roll journaled in parallel relation in said heads, means for securing said heads at the required turning adjustment, and means for feeding the material along said bed, substantially as set forth.

7. In a sizing and cutting machine for candy and the like, the combination of a supporting-frame, a bed secured to said frame, vertically-adjustable slides on said frame, heads or supports journaled on said slides and adapted for a turning adjustment thereon, a sizing-roll and a cutting-roll journaled in parallel relation on said heads, means for securing said heads at the required turning adjustment, and means for feeding the material along said bed, substantially as set forth.

8. In a sizing and cutting machine for candy and the like, the combination of a supporting-frame, a bed secured to said frame, heads or supports journaled in said frame and adapted for a turning adjustment, a sizing-roll and a cutting-roll journaled in parallel relation in said heads, means for securing said heads at the required turning adjustment, and a feed-roll journaled in the main frame beneath the rolls aforesaid, substantially as set forth.

9. In a sizing and cutting machine for candy and the like, the combination of a supporting-frame, a bed secured to said frame vertically-adjustable slides on said frame, heads or supports journaled on said slides and adapted for a turning adjustment thereon, a sizing-roll and a cutting-roll journaled in parallel relation on said heads, means for securing said heads at the required turning adjustment, and a feed-roll journaled in the main frame beneath the rolls aforesaid, substantially as set forth.

10. In a sizing and cutting machine for candy and the like, the combination of a supporting-frame, a bed secured to said frame, heads or supports journaled in said frame and adapted for a turning adjustment, a sizing and a cutting roll journaled in parallel relation in said heads, means for securing said heads at the required turning adjustment, the same comprising a disk carried by the journal-shaft of said heads and provided with peripheral notches and a spring latch-bolt on the main frame adapted for engagement with said notches, and means for feeding the material along said bed, substantially as set forth.

11. In a sizing and cutting machine for candy and the like, the combination of a supporting-frame, a bed secured to said frame, vertically-adjustable slides on said frame,

heads or supports journaled on said slides and adapted for a turning adjustment thereon, a sizing-roll and a cutting-roll journaled in parallel relation on said heads, means for securing said heads at the required turning adjustment, the same comprising a disk carried by the journal-shaft of said heads and provided with peripheral notches and a spring latch-bolt on the main frame adapted for engagement with said notches, and means for feeding the material along said bed, substantially as set forth.

12. In a sizing and cutting machine for candy and the like, the combination of a supporting-frame, a bed secured to said frame, heads or supports journaled in said frame and adapted for a turning adjustment, a sizing-roll and a cutting-roll journaled in parallel relation in said heads, means for imparting positive rotation to said sizing and cutting rolls, and means for feeding the material along said bed, substantially as set forth.

13. In a sizing and cutting machine for candy and the like, the combination of a supporting-frame, a bed secured to said frame, vertically-adjustable slides on said frame, heads or supports journaled on said slides and adapted for a turning adjustment thereon, a sizing-roll and a cutting-roll journaled in parallel relation on said heads, means for imparting positive rotation to said sizing and cutting rolls, and means for feeding the material along said bed, substantially as set forth.

14. In a sizing and cutting machine for candy and the like, the combination of a supporting-frame, a bed secured to said frame, heads or supports journaled in said frame and adapted for a turning adjustment, a sizing-roll and a cutting-roll journaled in parallel relation on said heads, a feed-roll journaled in the main frame beneath the rolls aforesaid, and means for imparting positive rotation to the sizing, cutting and feed rolls, substantially as set forth.

15. In a sizing and cutting machine for candy and the like, the combination of a supporting-frame, a bed secured to said frame, vertically-adjustable slides on said frame, heads or supports journaled on said slides and adapted for a turning adjustment thereon, a sizing-roll and a cutting-roll journaled in parallel relation on said heads, a feed-roll journaled in the main frame beneath the rolls aforesaid, and means for imparting positive rotation to the sizing, cutting and feed rolls, substantially as set forth.

16. In a sizing and cutting machine for candy and the like, the combination of a supporting-frame, a bed secured to said frame, heads or supports journaled in said frame and adapted for a turning adjustment, a sizing-roll and a cutting-roll journaled in parallel relation on said heads, the said cutting-roll comprising a series of circular blades secured together in separated relation and a series of

clearing-bars loosely arranged between said blades, and means for feeding the material along said bed, substantially as set forth.

17. In a sizing and cutting machine for 5 candy and the like, the combination of a supporting-frame, a bed secured to said frame, vertically - adjustable slides on said frame, heads or supports journaled on said slides and adapted for a turning adjustment thereon, a 10 sizing-roll and a cutting-roll journaled in parallel relation on said heads, said cutting-roll comprising a series of circular blades secured together in separated relation and a series of 15 clearing-bars loosely arranged between said blades, and means for feeding the material along said bed, substantially as set forth.

18. In a sizing and cutting machine for 20 candy and the like, the combination of a supporting-frame, a bed secured to said frame, heads or supports journaled in said frame and 25 adapted for a turning adjustment, a sizing-roll and a cutting-roll journaled in parallel relation on said heads, the said cutting-roll comprising a series of circular blades secured together in separated relation and a series of

clearing-bars loosely arranged between said blades, and a feed-roll journaled in the main frame beneath the rolls aforesaid, substantially as set forth.

19. In a sizing and cutting machine for 30 candy and the like, the combination of a supporting-frame, a bed secured to said frame, vertically - adjustable slides on said frame, heads or supports journaled on said slides and adapted for a turning adjustment thereon, a 35 sizing-roll and a cutting-roll journaled in parallel relation on said heads, said cutting-roll comprising a series of circular blades secured together in separated relation and a series of 40 clearing-bars loosely arranged between said blades, and a feed-roll journaled in the main frame beneath the rolls aforesaid, substantially as set forth.

Signed at Chicago, Illinois, this 2d day of December, 1904.

GEORGE F. DICKSON.
